190,039

FLOWER POT

William John White, 991 S. State Road 7, Fort Lauderdale, Fla., and Louis Besterda, Fort Lauderdale, Fla.; said Besterda assignor to said White

Filed June 13, 1960, Ser. No. 60,946

Term of patent 14 years

(Cl. D35—3)

Fig. 2

Fig. 4

Fig. 1

Fig. 5

Fig. 3

Figure 1 is a side elevational view of a flower pot showing our new design,

Figure 2 is a top plan view thereof,

Figure 3 is a bottom plan view of Figure 1,

Figure 4 is a sectional view taken along line 4—4 of Figure 1, and

Figure 5 is a sectional view taken substantially along line 5—5 of Figure 1.

We claim:

The ornamental design for a flower pot, as shown.

References Cited in the file of this patent

UNITED STATES PATENTS

D. 120,794	Ziska	May 28, 1940
664,185	Stran	Dec. 18, 1900
1,190,203	Sorge	July 4, 1916

FOREIGN PATENTS

17,971	Great Britain	1896
58,857	France	Nov. 25, 1953

OTHER REFERENCES

Butler Manufacturing Co., advertisement, received June 14, 1937, front, upper right corner,